United States Patent Office

Des. 179,488
Patented Jan. 1, 1957

179,488

FAN HEATER OR SIMILAR ARTICLE

Walter E. Moore, Stratford, and John A. Russo, Bridgeport, Conn., assignors to General Electric Company, a corporation of New York

Application March 7, 1956, Serial No. 40,501

Term of patent 14 years

(Cl. D81—10)

Fig. 1.

Fig. 2.

Fig. 3.

Fig. 4.

In the drawings:

Figure 1 is a front perspective view of a fan heater or similar article embodying our new design;

Figure 2 is a side elevational view thereof;

Figure 3 is a front elevational view thereof; and

Figure 4 is a top plan view thereof.

The essential features of our design reside in the portions shown in full lines.

We claim:

The ornamental design for a fan heater or similar article, substantially as shown and described.
